(57) CLAIM

The ornamental design for a disposable bandeau bra, as shown and described.

DESCRIPTION

FIG. 1 is a perspective view of the disposable bandeau bra showing my new design;

FIG. 2 is a front elevational view of the disposable bandeau bra, shown in FIG. 1; and,

FIG. 3 is a rear elevational view of the disposable bandeau bra, shown in FIG. 1.

The broken lines at the center of the disposable bandeau bra are understood to represent stitching.
